UNITED STATES PATENT OFFICE.

OTIS G. GRAHAM, OF PORTLAND, OREGON.

FILTER-FUNNEL.

1,170,892.

Specification of Letters Patent.

Patented Feb. 8, 1916.

Application filed March 2, 1915. Serial No. 11,504.

To all whom it may concern:

Be it known that I, OTIS G. GRAHAM, a citizen of the United States, residing at Portland, in the county of Multnomah and State of Oregon, have invented certain new and useful Improvements in Filter-Funnels, of which the following is a specification.

My invention relates to funnels for filling tanks and other receptacles, and especially to funnels adapted to remove solid matter from the liquid being poured, as well as to separate two liquids of different specific gravities, as oil and water, or the like.

The objects of my invention are, first, to provide a funnel that shall remove from the liquid all solid matter; second, to provide a funnel that shall remove any foreign liquid of heavier specific gravity that may be intermixed with the liquid being poured; third, to provide a funnel from which the removed liquid of heavy specific gravity may be easily drained after pouring has ceased; fourth, to provide a funnel that is simple in construction, positive in operation, strong, and cheap to manufacture.

I attain the above objects by means of the construction described in these specifications, and illustrated in the accompanying drawing, which therefore becomes a part of this application for Letters Patent.

Like characters designate like parts throughout the several views of the drawing, in which—

Figure 1 is a plan view of a funnel embodying my invention, the view as shown being partially broken away to better illustrate the several parts; Fig. 2 is a longitudinal vertical section of a funnel embodying my invention.

Referring to the drawing, numeral 1 is the receiving portion of the funnel and 2 is the discharging portion, portions 1 and 2 being integrally connected by a conical portion 3, as shown in Fig. 2. The discharge portion 2 has an extension 4 within the conical portion 3, said extension terminating approximately slightly below the junction point portion 1 and conical portion 3, as shown in Fig. 2.

A straining member 5, in the shape of a diaphragm is inserted in portion 1, and is securely attached (by solder or other convenient means) to extension 4 of discharge member 2. Said straining member may be of any desired or suitable woven material,

the illustration showing a very fine mesh wire gauze.

A deflecting member 6 is mounted upon the straining member 5 in such a manner as to deflect the liquid being poured toward the side of receiving portion 1 of the funnel, whence the liquid passes downward through the exposed annular portion of the screen 5, between members 6 and 1, into conical portion 3. At this point the liquid is caused to turn upward in its flow, and should there be present in the liquid being poured a small amount of any foreign liquid of heavier specific gravity, the change of direction of flow will cause a separation of the two liquids, the heavier foreign liquid remaining in the conical portion 3, while the lighter liquid passes upward through that annular portion of screen 5 included between member 6 and extension 4, and then downward through that portion of screen 5 included within the periphery of extension 4, and thus out through discharge portion 2. A baffle plate or collar 7 may be attached to extension 4 to provide against the inertia of the foreign liquid causing same to impinge against extension 4 with sufficient force to create a vertical component sufficient to carry said heavy liquid over into extension 4.

A drain pipe 8 is provided for the purpose of removing the liquid residue remaining in cone 3 after the pouring has ceased.

An annular lip 8^a is provided upon portion 1 to prevent overflowing the funnel when in use.

My invention may be made of any size and constructed of any materials deemed suitable and convenient for a device of this character, and while I have illustrated and described a preferred construction and arrangement of parts deemed advisable in materializing my invention, I wish to include in this application for Letters Patent all mechanical equivalents or substitutes that may fairly be considered to come within the scope and purview of my invention as defined by the appended claims.

Having thus disclosed my invention, what I claim is:

1. A funnel comprising a receiving chamber, a discharge member, a separating chamber adjacent said receiving chamber and intermediate said receiving chamber and said discharge member, a straining dia-

phragm within said receiving chamber, said diaphragm extending across the upper end of said discharging member and being intermediate said receiving chamber and said separating chamber, a deflector within said receiving chamber, and a tube for draining said separating chamber.

2. In a funnel having a cylindrical portion and a truncated conical portion, a screen diaphragm within said cylindrical portion and attached to the walls thereof, a discharge tube within said conical portion, said tube being attached to said diaphragm and extending outside of said conical por-

tion, an inverted dish shaped disk mounted upon said diaphragm within the cylindrical portion of said funnel, the periphery of said disk being intermediate the periphery of the cylindrical portion of said funnel and the periphery of said discharge tube.

In testimony that I claim the foregoing as my own, I have hereunto affixed my signature in the presence of two subscribing witnesses.

OTIS G. GRAHAM.
